UNITED STATES PATENT OFFICE.

THOMAS MITCHELL, OF CHESTER, PENNSYLVANIA, ASSIGNOR TO DANIEL EAGAN, OF PHILADELPHIA, PENNSYLVANIA.

BOLSTER.

SPECIFICATION forming part of Letters Patent No. 728,270, dated May 19, 1903.

Application filed June 20, 1902. Serial No. 112,421. (No model.)

To all whom it may concern:

Be it known that I, THOMAS MITCHELL, a citizen of the United States, residing at Chester, in the county of Delaware and State of Pennsylvania, have invented certain new and useful Improvements in Bolsters, of which the following is a specification.

My improvements relate to bolsters of the type known as the "box" form, and which are conveniently made of cast steel. In the construction of bolsters, it is desirable to so fashion them as to combine, as far as possible, lightness and strength, so that the least possible quantity of metal will be consumed or employed in producing a bolster adapted to support a given load or resist given strains.

Such diminution of weight as is consistent with the requisite strength, is desirable in a bolster not only because proportionate to the lightness is a diminution of first cost, by reason of the diminished amount of metal required in construction, but also because diminution of the weight of the bolsters represents a proportionate economy in the propulsion of the cars in connection with which they are employed.

It is the object of my invention to produce a bolster of such form that it will possess greater strain resisting capacity, in proportion to the amount of metal required in its construction, than kindred bolsters as heretofore made.

In the accompanying drawings I show, and herein I describe, a good form of a convenient embodiment of my invention, the particular subject-matter claimed as novel being hereinafter definitely specified.

In the drawings,

Figure 1 is a view partly in vertical longitudinal section, and partly in side elevation, of a bolster embodying my invention.

Figure 2 is a view in top plan of the bolster shown in Figure 1.

Figure 3 is a view in end elevation of the bolster.

Figure 4 is a transverse section on the dotted line 4-4 of Figure 2.

Figure 5 is a transverse section on the dotted line 5-5 of Figure 2.

Similar letters of reference indicate corresponding parts.

The bolster shown in the accompanying drawings happens to be a truck bolster. It is, however, to be understood that the invention in its broader aspect is applicable in connection with either body or truck bolsters.

The truck bolster *a*, shown in the drawings, is of general box form, and is provided with the usual center bearing *b*, side bearings *c*, top plate *d*, side walls *e*, and pairs of vertically extending column guides *f*. *g* is a sleeve for the king pin, said sleeve being shown as formed as integral with and connective of the top and bottom plates.

h are flanges laterally projecting from the respective sides of the bolster, in the plane of the top plate. Said flanges, which are shown as of length less than that of the bolster, and as terminating respectively at points about abreast of the respective side bearings, are preferably of considerable breadth at the center of the bolster, and gradually diminish in breadth from their centers to their ends.

The bottom plate or wall *i* is for a region preferably of length less than that of the bolster, and extending conveniently from a point about in line below one side bearing to a point about in line below the other side bearing, arranged to form an elongated concavity, preferably of the full width of said plate—that is to say, the bottom plate, which is preferably of about uniform thickness from edge to edge, inclines in the region referred to, upwardly from its respective side edges to the vicinity of the major axis of the said plate. The said plate is, therefore, so to speak, inwardly curved, shaped or bent,—or, expressed broadly, embodies a concavity. Said concavity is of considerable depth at the central portion of the bolster, and becomes gradually shallower at its respective ends as shown. The bottom plate at the respective ends of the bolster is preferably flat.

In the bolster illustrated, the longitudinally extending concavity is of angular, that is to say, approximately V-shaped, section.

The concavity may, however, vary in its sectional profile at the will of the constructor.

I prefer, in the interest of lightness and economy of metal, not to form said bottom plate or wall as transversely continuous at all points, but to provide or form in it openings 5 such as those designated *j*.

The openings *j* may, of course, be omitted, or they may be made of any desired form and size.

The bolster herein described is designed to 10 be made as a single integral casting of steel.

Having thus described my invention, I claim—

1. A cast steel box bolster, the respective 15 sides of the bottom wall or plate of which, at the intermediate portion of the structure, incline upwardly from the outer edges, to the region of the major axis of said wall or plate.

2. A bolster having a wall embodying a longitudinally extending concavity in breadth 20 approximately equal to its own.

3. A bolster having a wall or plate of approximately V-shaped section, substantially as set forth.

4. A bolster of box form, the bottom wall 25 or plate of which embodies a longitudinally extending concavity of breadth approximately equal to its own.

5. A cast steel box bolster, the bottom wall or plate of which, at the intermediate portion 30 of the structure, is upwardly inclined from its respective edges to the region of the major axis of said wall or plate, the concavity thus formed being of the full breadth from side wall to side wall of the bolster, and said 35 concavity being of less length than the bolster.

6. A bolster of the box form, the central portion of the bottom wall or plate of which is upwardly inclined from its respective edges 40 to the region of the major axis of said wall or plate, the concavity thus formed being approximately equal to the breadth of said bottom plate, said bolster having a king bolt sleeve integral with its top and bottom walls 45 or plates.

7. A bolster of box form, the bottom wall

or plate of which embodies a concavity of breadth approximately equal to its own, and is provided with openings, said bolster having a king bolt sleeve integral with its top 50 and bottom plates.

8. A bolster of box form, the bottom wall or plate of which embodies a concavity of breadth approximately equal to its own, and of gradually diminishing depth at its respective ends, said plate having openings formed in its concave region, said bolster having a king bolt sleeve integral with the top and bottom walls or plates. 55

9. A box bolster having a top plate, an inwardly - curved bottom plate, a king bolt sleeve extending from the central region of the curved bottom plate to the top plate, and integral with both, and flanges formed at the respective sides of the top plate of the bolster. 60

10. A box bolster having a top plate, an inwardly - curved bottom plate, a king bolt sleeve extending from the central region of the curved bottom plate to the top plate and 70 integral with both, and flanges formed at the respective sides of the top plate of the bolster, said flanges being of a given width at the center of the bolster, and tapering toward their respective ends. 75

11. A bolster of box form the bottom plate or wall of which is flat at its respective ends and in its central portion embodies a longitudinally-extending concavity.

12. A bolster of box form the bottom plate or wall of which is flat at its respective ends and in its central portion embodies a longitudinally-extending concavity, said bottom plate or wall embodying in its concave region a series of openings. 80

In testimony that I claim the foregoing as my invention I have hereunto signed my name this 12th day of June, A. D. 1902.

THOMAS MITCHELL.
